ELLISON S. PURINGTON, OF GLOUCESTER, MASSACHUSETTS, ASSIGNOR TO JOHN HAYS HAMMOND, JR.

RECEPTION OF VARYING FREQUENCY SIGNALS

Application filed May 18, 1929. Serial No. 364,221.

This invention relates to a method of receiving signals from continuous wave transmitters which are so unsteady in the frequency radiated that they cannot be readily received by the usual methods. For example, a transmitter may vary as much as 1 KC in frequency during the course of transmission of a message due to miscellaneous causes, such as swinging antennas and varying power supplies.

19 It is an object of this invention to permit reception of such unsteady or wobbled transmissions.

It is an object of this invention to make it possible to receive continuous frequency signals with constant pitch in the indicating phones in spite of variations in the frequency transmitted.

A still further object of this invention is to provide a new and improved system for uninterrupted radio transmission.

A further object of this invention is to produce a pure tone from a signalling radiation purposely scattered amongst several frequency channels at successive times, for producing secrecy of transmission.

25 A further object is to produce a reception means from a signalling radiation purposely scattered among several frequency channels at successive times in order to minimize selective fading.

These and other objects will become apparent from the following description taken in connection with the accompanying drawing.

This system accomplishes the above objects 35 by using two local oscillators at the receiver of approximately the same frequency as the incoming radiations. This may be considered to constitute the double superheterodyne. In carrying out the system of this invention 40 three or more detectors are provided, the usual first detector of the superheterodyne circuit, and two intermediate detectors.

The figure represents a receiving circuit 45 embodying my invention. In this figure the antenna circuit 1 comprises an antenna, an input inductance, and the ground connection, and is adapted to receive the incoming frequency which I have designated as W. Inductively related to the inductance of the antenna circuit is a broadly tuned oscillatory

circuit 2 connected to the grid and filament of the detector 3 in the usual and well known manner through the grid leak 4 and the grid leak condenser 5. Also inductively related to the inductance of the oscillatory circuit 2 are the outputs of the local oscillatory circuits 6 and 7 which are adapted to produce the two heterodyning frequencies which are designated as M and N. The detector tube 3 has included in its output circuit a closed oscillatory circuit 8 the inductance of which is inductively related to the input inductance 9 of the filter amplifier 10 which is of the usual band pass type and adapted to transmit frequencies of M-W and W-N. This filter amplifier 10 also includes as many intermediate frequency amplifier stages as may be desirable to properly amplify the selected frequencies, and is similar to the intermediate frequency amplifier of the usual superheterodyne circuit, except for the fact that it is rather more broadly tuned in order to practically equally amplify throughout a slightly varying range of frequencies.

In place of detector 3, I may substitute 75 a pair of detectors, one of which receives part of the incoming energy and also energy from M, producing M-W, the other which receives part of the incoming energy and also energy from N, producing W-N, said outputs of the two detectors being subsequently combined in amplifying filter 10. In this manner the input to 10 may be substantially free from the difference frequency M-N occurring when one detector only is used.

The output 11 of the filter amplifier 10 is connected to the input inductance 12 of the detector 13, included in the input circuit of which is the grid leak 14 and the grid leak condenser 15. The output of this second detector 13 includes an inductance 16 inductively related to the inductance 17 constituting the input of the filter 18. This filter 18 is adapted to pass frequency M-N and excludes all other frequencies.

The output 19 of the filter 18 is inductively related to the input inductance 20 of the third detector 21 included in the input circuit of which is the grid leak 22 and the grid leak condenser 23.

Also inductively related to the inductance 20 of the detector 21 is the output inductance of the local oscillator 24 which is adapted to produce a frequency $(M-N) \pm A$.

5 The output of the third detector 21 includes an audio frequency device 25 and a high frequency bypass condenser 26.

Each of the detector circuits is provided with the usual filament and plate sources as 10 shown.

Having thus described my invention, I will now describe its operation. As above noted, I described the incoming signal frequency as W. This incoming signal is a continuous 15 wave keyed to produce the signal but unsteady as to frequency. The two auxiliary frequencies M and N produced by the local oscillator are so arranged as to be constant and are adjustable so that the difference M-N 20 may be kept constant preferably, for example, with M greater than the received signal W and N less than the received signal W by a substantially different amount. For instance, as follows: $M-W=0.4$ $(M-N)$ and $W-N=25 0.6$ $(M-N)$.

When the three waves M, N, and W are impressed upon the first detector 3 of the figures, there will be produced by the process of detection, among other currents the frequencies 30 $M-N$, $M-W$, and $W-N$, of which the first, $M-N$, is a constant frequency, constant amplitude current. The two remaining currents $M-W$ and $W-N$ exist only when there is an incoming signal, and vary in frequency as a 35 result of the unsteadiness or wobble of the incoming wave W. These three currents are impressed on the first amplifying filter 10 which comprises, as described above, amplifiers and other equipment so arranged as to 40 selectively amplify the currents of frequencies in the range of $M-W$ and $W-N$, but reject currents of the frequency $M-N$, the remaining currents of frequencies $M-W$ and $W-N$ existing as stated above only when there is 45 an incoming signal impressed upon the second detector 13.

It is well known in the mathematical treatment of detector actions that when voltages of two frequencies are impressed upon a detecting device, or any electrical device possessing a nonlinear characteristic, with respect to the relation between input and output, there will be produced a current of frequencies equal to the sum of the impressed frequencies, 50 a current of a frequency equal to the difference of the impressed frequencies, and also the first harmonics or overtones of the impressed frequencies. In the usual process of detection, the difference frequency is that 55 utilized, but in the present invention, with W intermediate between N and M, I utilize the sum frequency and the other frequencies are rejected by means of the filter 18. Thus, the sum frequency due to the detecting of $M-W$ 60 and $W-N$, which is $M-N$, is the only fre-

quency retained and is a current of constant frequency regardless of frequency variations in W. Furthermore, as no input will exist on the detector 13 in the absence of W, there will be no current in the output of filter 18 when there is no signal being received.

The current passed by the filter 18 is then impressed on the input of the third detector which serves to combine this frequency with the locally produced frequency $(M-N) \pm A$. This third detector thus produces an audio current A which, as can be readily seen, is of constant pitch regardless of the frequency of the incoming signal. The various other frequencies resulting from the combination of the frequency $(M-N) \pm A$ and the sum frequency $M-N$ passed by the filter 18 are eliminated in the audio circuit as A is the only audible frequency present.

In case M and N are both greater or both less than W, the second filter 18 utilizes the difference frequency in the usual manner, but this arrangement is not the preferable arrangement, because of the need of broader radio tuning to admit the three wave frequencies.

By a proper choice of W, M, and N, and by having $M-N$ sufficiently above audibility, there will be no overlapping of the undesired unsteady current with the desired current of frequency of $M-N$. Such proper relationship exists, for instance, when $M-W=0.4$ $(M-N)$ and $(W-N)=0.6$ $(M-N)$ and when $M-N$ is above audibility. Thus, with a carrier frequency of 1,000 KC and $M-N=10$ KC M would be 1,004 KC and N 994 KC. This current of $M-N$ impressed upon the second detector, it must be remembered, exists only when there is an incoming signal, and any steady and unkeyed current of frequency $M-N$ due to the beating of the local oscillator M and N, producing currents of this frequency in the plate of the first detector, must be sufficiently prevented from reaching the third detector by the first filter 18 and by the usual methods of shielding.

If the incoming signal is a modulated signal, the frequency resulting from the second detector action is rendered audible by a non-oscillating third detector, and the local oscillator producing $(M-N) \pm A$ is not used. However, if continuous frequency signals are being received, the local oscillator 24 is used as described to beat with the frequency $M-N$ in the input of the third detector, resulting in a tone of constant pitch A, being received in the indicating headphones whenever there is an incoming signal.

Having thus described my invention, it is to be understood that I am not to be limited by the specific embodiments of my invention shown and described herein for the purpose of illustration, but by its scope as set forth in the appended claims.

I claim:

1. Means for the reception of variable frequency signals which comprises an input circuit, a first detector, an input circuit for said first detector, a local oscillator producing a high frequency differing from the received frequency, a second local oscillator for producing a low frequency differing from the incoming frequency by an amount which is different than the difference of the first local oscillator therefrom, an output circuit for said first detector, a filter circuit inductively related to said output circuit, and adapted to filter from the output of said first detector all frequencies except the difference frequency between the high heterodyning frequency and the received frequency, and the difference frequency between the received frequency and the low heterodyning frequency, and to amplify the frequencies passed, a second detector associated with the output of said filter circuit for combining the two difference frequencies existing in the output of said first filter, a second filter for removing from the output of said second detector all frequencies except the frequency produced by said last combining, corresponding to the difference of the two local oscillators, a third detector associated with the output of said last mentioned filter, a third heterodyning frequency source for producing a frequency which, when combined with said last produced frequency, will cause a constant audio frequency, and a utilization circuit for said audio frequency.

2. Means for the reception of variable frequency signals which comprises, a local oscillator for producing a high frequency differing from the received frequency, a second local oscillator for producing a low frequency differing from the received frequency, differently than the first local oscillator, a first detector for combining the received frequency and the locally produced frequencies, a filter circuit adapted to filter from the output of said first detector all frequencies except the difference frequency between the high heterodyning frequency and the received frequency, and the difference frequency between the received frequency and the low heterodyning frequency, and to amplify the frequencies passed, a second detector for combining the two difference frequencies passed by said first filter, a second filter for removing from the output of said second detector all frequencies except the sum frequency produced by said last combining, equal to the difference of the two local frequencies, a third heterodyning frequency source for producing a frequency which, when combined and detected with said last produced frequency, will cause a constant audio frequency, a third detector for combining the said frequency and the last mentioned heterodyning frequency, and a utilization

circuit for the audio frequency produced by said combining.

3. Means for the reception of variable frequency signals which comprises, two local oscillators for producing frequencies differing by a different amount from a received frequency, a single first detector for combining the received frequency and the locally produced frequencies, an amplifier and filter circuit adapted to filter from the output of said first detector all frequencies except the difference frequencies between the two heterodyning frequencies and the received frequency, and to amplify the frequencies passed, a second detector for combining the two difference frequencies passed by said first filter, a second filter for removing from the output of said second detector all frequencies except the sum frequency produced by said last combining equal to the difference of the two heterodyning frequencies, a third heterodyning frequency source for producing a frequency which, when combined with said last produced frequency, will cause a constant audio frequency, and a third detector last for producing said constant audio frequency.

4. Means for the reception of variable frequency signals which comprises, means for producing three heterodyning frequencies, means for combining the received frequency with two of the heterodyning frequencies, means for filtering from the output of said combining means all frequencies except the difference frequencies between the heterodyning frequencies and the received frequency produced by said combining means, a second combining means associated with the filtering means for combining the two resulting difference frequencies, a second filtering means for removing from the output of said second combining means all frequencies except the sum frequency produced by said last combining equal to the difference of the first two heterodyning frequencies, and a third combining means associated with the output of said last mentioned filtering means for combining the third heterodyning frequency with the last mentioned difference frequency and thus producing an audio frequency.

5. Means for the reception of variable frequency signals which comprises, means for producing three heterodyning frequencies, means for combining the received frequency with two of the heterodyning frequencies, means for filtering from the output of said combining means all frequencies except the difference frequencies between the heterodyning frequencies and the received frequency produced by said combining means, a second combining means associated with the filtering means for combining the two resulting difference frequencies, a second filtering means for removing from the output of said second combining means all frequencies except the sum frequency produced by said last

- combining, equal to the difference of the first two heterodyning frequencies, a third combining means associated with the output of said last mentioned filtering means for combining the third heterodyning frequency with the frequency equal to the difference of the first two heterodyning frequencies, and thus producing an audio frequency, and a utilization circuit for said audio frequency.
6. The method of reception of signal energy which comprises, combining the incoming signal energy with locally generated oscillations having a frequency higher than the frequency of the incoming signal energy and with locally generated oscillations having a frequency lower than the frequency of the incoming energy, each of said locally generated frequencies differing from the incoming frequency by a different amount, producing from said combination energy having a frequency equal to the frequency of the incoming energy minus the frequency of the second named locally generated energy and also energy of a frequency equal to the frequency of the first named locally generated energy minus the frequency of the incoming energy, combining the two resulting frequencies and producing therefrom energy having a frequency equal to the difference between the two locally generated frequencies, combining the last resulting energy with energy having a frequency differing therefrom by an audible frequency and producing from said last combination audible frequency energy.
